OPERATING DEVICE FOR HOOKLESS OR
SLIDE FASTENERS

Lillian I. Scheldorfer, Fort Lauderdale, Fla.

Application July 19, 1951, Serial No. 237,563

2 Claims. (Cl. 294—26)

1

This invention relates to actuating devices for facilitating the operation of hookless or slide fasteners, and particularly for actuating such fasteners associated with garments and so placed where accessibility for manipulation is frequently inconvenient, awkward and difficult.

The present invention is particularly directed to such devices as above generally referred to and which include in combination a shield for preventing the fastener elements from entanglement with the cloth of the garment and the skin of the wearer during the closing operation.

Operating devices now known and employed to facilitate closing or opening slide fasteners and which include in combination a shield for the most part bulky and entail relatively expensive fabrication processes. It is, therefore, a primary object of the present invention to provide a shield equipped slide fastener operating device that is extremely simple in terms of structure, is pleasing and attractive in appearance, can be manufactured economically and at the same time possesses all of the desirable advantages of a shield equipped operating device for slide fasteners.

The slide fastener operating device of this invention is characterized by having the shield thereof as a prolongation of the main body portion of the device at that end of the device equipped for attachment to the slider of the hookless fastener so that the shield is substantially in a plane normal to the plane of the main body portion of the device, thereby eliminating all bulkiness and resulting in the shield more efficiently functioning for preventing the cloth of the garment or the skin of the wearer becoming entangled with the fastener elements incidental to the desired operation of the slide fastener.

The invention, together with its objects and advantages, will be best understood when the following detailed description is read with reference to the accompanying drawing wherein are illustrated what are presently considered preferred embodiments of the invention, and in which:

Figure 1 is a face view of a device embodying this invention and diagrammatically illustrating it in position for closing a slide fastener;

Figure 2 is a side elevational view of the slide fastener shown in Figure 1;

Figures 3, 4 and 5 are views similar to Figure 2, but respectively illustrating slightly modified forms of the invention.

In Figure 1 there is fragmentarily illustrated

a garment 5, such as a dress, equipped with a conventional slide fastener provided with the usual stringers 6, a slider 7 for engaging and disengaging the hooks of the stringer, and a pull tab or finger piece 8 pivoted to the slider 7 and provided with a perforation 9, all of which is also conventional in fasteners now in common use.

The device of this invention is adapted to be releasably secured to the finger piece or pull tab 8 to facilitate opening and closing of the slide fastener and to shield the skin of the user and/or undergarments from being entangled or caught between the hooks of the stringers 6.

In each of the forms of the invention, the actuating device for the hookless fastener is formed from a single length of suitable material, as for example, metal, plastic or the like, cut, shaped and dimensioned to provide an elongated body or shank 10 equipped at one end with a handle 11 and at an opposite end with a shield portion 12. In forming the handle 11, the material of the device is curved in one direction, and in forming the shield 12 the material of the device is curved in a direction other than that of the handle 11 so that the handle 11 extends from the shank or body 10 in a direction different from that direction in which the shield 12 extends so that neither will interfere with the proper function of the other.

At the juncture of the shank or body 10 and shield 12, the body or shank 10 is provided with a rivet 13 fabricated to provide a hook 14 that also extends laterally from the device in a direction opposite to that of the shield 12.

As shown to advantage in Figure 1, when the device is employed for manipulating a slide fastener, as for example, for closing the latter, the hook 14 is engaged in the perforation 9 of the finger piece or pull tab 8 with the shield 12 disposed at the inner side of the garment and curving away from the slide fastener for contact with the inner garment or skin of the wearer, as the case may be. The shield 12 being longitudinally curved serves to hold the elements of the slide fastener away from the inner garment or flesh of the user and thus positively prevent entanglement of the inner garment or flesh with the elements of the stringers 6. With the device in proper engagement with the slide fastener as shown in Figure 1, the handle portion 11 is readily accessible at the opening of the garment and accordingly may be conveniently engaged with the finger of the hand of the user, as shown in Figure 1, or alternately engaged with a string

or the like, and the device pulled straight upwardly for moving the slider 7 in a corresponding direction to interengage the elements of the stringers 6 and thus close the opening 15.

It is also apparent that the device of this invention may be used to facilitate opening of the fastener, and of course in this operation no shield is required. No detailed explanation of the manner of using the device for opening the fastener is believed necessary; it being apparent that to perform such operation with this device, the hook 14 is engaged in the aperture or perforation of the pull tab 8, and with the finger engaging in the handle 11 the device is pulled straight downwardly causing the slider 7 to be moved downwardly to disengage the elements of the stringers 6 and thus open the opening 15.

It is apparent from the foregoing that the device of this invention lends itself to a variety of shapes without departing from the inventive concept or detracting from the operating advantages of the device. In this connection it may be noted that, as shown in Figures 1, 2, 4 and 5, the shank or body 10 may be straight throughout its entire length, or as shown in Figure 3 the shank or body 10 may be slightly curved in the direction of its length. Also, and as shown in Figures 3 to 5 inclusive, the shank or body 10 may be of uniform width throughout its length or, as shown in Figures 1 and 2, the shank or body 10 intermediate the ends thereof may be reduced in width as indicated generally at 16.

Also, the handle 11 may, as shown in Figures 1 and 2, be in the form of an open hook or, as shown in Figures 3 to 5 inclusive, the handle may be in the form of a closed loop or eye. Likewise and as shown in Figures 1 to 4 inclusive, the handle 11 may extend from the shank 10 in a plane normal thereto or, as shown in Figure 5, may extend from the shank at substantially right

angles thereto at either edge side of the shank.

While the invention has been described in detail in its presently preferred embodiments, it will, of course, be understood that such has been done for purposes of illustration only and not by way of limitation, and therefore only such limitations are to be imposed thereon as may reasonably come within the scope of the appended claims.

What is claimed is:

1. A device for manipulating slide fasteners comprising an elongated shank one end of which is reversely turned to provide a finger engaging hook, the other end of the shank being curved in the opposite direction to provide a body engaging shield, and an upwardly extending hook on the shank, near the shield end of the latter, projecting in the direction opposite to the shield and engageable with the pull tab of the slide fastener.

2. A device for manipulating slide fasteners comprising an elongated shank narrow throughout its length, one end of said shank being reversely turned to provide a finger engaging hook, the other end of the shank being curved in the opposite direction to provide a body engaging shield, and an upwardly extending hook on the shank, near the shield end of the latter, projecting in the direction opposite to the shield and engageable with the pull tab of the slide fastener.

LILLIAN I. SCHELDORFER.
